UNITED STATES PATENT OFFICE.

CHARLES T. WESTLAKE, OF ST. LOUIS, MISSOURI, ASSIGNOR TO DOUBLE BODY BOLSTER COMPANY, OF ST. LOUIS, MISSOURI, A CORPORATION OF NEW JERSEY.

CENTER-BOLSTER FOR SIX-WHEEL CAR-TRUCKS.

1,102,620.

Specification of Letters Patent.

Patented July 7, 1914.

Application filed August 11, 1913. Serial No. 784,246.

To all whom it may concern:

Be it known that I, CHARLES T. WESTLAKE, a citizen of the United States, residing at city of St. Louis, State of Missouri, have invented a certain new and useful Improvement in Center-Bolsters for Six-Wheel Car-Trucks, of which the following is a full, clear, and exact description, such as will enable others skilled in the art to which it applies to make and use the same, reference being had to the accompanying drawings, forming part of this specification, in which—

Figure 1 is a plan view of a center bolster of my improved construction. Fig. 2 is a sectional view taken approximately on the line 2—2 of Fig. 1. Fig. 3 is a section taken on the line 3—3 of Fig. 1.

My invention relates generally to car trucks, and more particularly to the center bolster for six wheel trucks of the type shown in Patent No. 1,054,697.

In six wheel trucks having a one piece center bolster, the latter is usually formed so as to clear and accommodate other parts of the truck, and thus the end members of the center bolster or those parts which combine with the side frames or wheel pieces of the truck are subjected to eccentric stresses which are produced by the vertical load carried by the center bolster while other parts of the center bolster are subjected to torsional stresses. To effectually resist these eccentric and torsional stresses I propose to produce a center bolster which is formed in one piece preferably by casting, and parts of which bolster are formed and shaped in cross section so as to utilize to the best advantage the strength of metal of which the bolster is constructed in resisting service strains and stresses, thus providing a bolster which has the requisite strength, and at the same time is comparatively light in weight.

To the above purposes my invention consists in certain novel features of construction and arrangement of parts hereinafter more fully described and claimed.

My improved center bolster, as shown, is formed in a single piece preferably by casting, and the main body portion of said bolster comprises a pair of longitudinally disposed parallel members 10, which are preferably of I-beam shape in cross section, and a pair of transversely disposed end members

11, which are preferably channel shape in cross section with their horizontal flanges inwardly presented. The central portions of the members 10 are slightly arched as designated by 12 in order to accommodate the center axle of the truck and formed on or fixed to these arched portions are center bearing members 13. Formed integral with the central portions of the members 10, and transversely arranged between the same is a horizontally disposed plate 14, the central portion of which is slightly depressed as designated by 15 to form a center bearing, and formed integral with the central portion of said plate in the center of said center bearing is a vertically disposed cylindrical boss 16 which is preferably perforated to receive a king pin.

Formed integral with the members 10 and plate 14 and depending from said plate is a pair of vertically disposed parallel webs 17 which are adapted to straddle the center axle of the truck, and formed integral with the lower portions of these webs are horizontally disposed flanges 18 which are outwardly presented, and which join with the inwardly presented bottom flanges of the members 10.

Arms 19 which are preferably box-shape in cross section project outwardly from the corners of the rectangular frame formed by the members 10 and 11 and the inner ends of said arms merge with the end portions of said members 10 and 11. Portions of the inner vertical walls of the arms 19 are inset as designated by 19^a to form recesses or spaces for brake head clearance. Thus the portions 19 of the center bolster in nowise interfere with the free operation of the brake beams, and carried parts which are positioned beneath the bolster. Formed integral with the outer ends of these arms 19 are box-shaped members 20 which occupy positions between suitably arranged vertical guides on the side frames or wheel pieces A of the truck frame and the undersides of these members 20 are adapted to receive and rest upon springs which are carried by said side frames or wheel pieces.

If desired, vertically disposed guide ribs 21 may be formed on the side faces of the box-shaped members 20, and which ribs normally bear against the pedestals or guides on the side frames.

In one piece center bolsters of the type to which my invention relates, the vertical load produces eccentric stresses in the arms which project from the body of the bolster into the side frames or wheel pieces, and in order to resist these stresses I make the projecting arms 19 box shape in cross section, thus producing a construction which is comparatively light in weight, and at the same time 10 has ample strength to resist such stresses.

In the main body portion of the bolster the members 10 and 11 are shaped in cross section so as to utilize to best advantage the strength of metal to which said parts are composed, and thus a one piece center bolster is produced, which is comparatively light in weight, has great strength and rigidity, and which can be readily formed in a single piece by casting.

20 It will be readily understood that minor changes in the size, form and construction of the various parts of my improved center bolster for six wheel car trucks, can be made and substituted for those herein shown and 25 described, without departing from the spirit of my invention, the scope of which is set forth in the appended claims.

I claim:

1. A center bolster for six wheel trucks 30 comprising a rectangular frame the central portion of which is arched to accommodate the center axle of the truck, and arms projecting laterally from the corners of said frame, which arms are box-shape in cross 35 section, and the outer ends of which are adapted to coöperate with the wheel pieces of the truck frame.

2. A bolster for six wheel trucks comprising a body formed of pairs of flanged side 40 and end members the central portions of which side members are arched to accommodate the center axle of the truck, and arms integral with and projecting outwardly from the ends of said body, which arms are 45 box-shape in cross section.

3. A center bolster for six wheel trucks comprising a pair of longitudinally disposed parallel flanged members the central portions of which members are arched to 50 accommodate the center axle of the truck, a pair of transversely disposed parallel flanged members, and arms integral with and projecting outwardly from the end portions of said pairs of parallel members and 55 which arms are box-shape in cross section.

4. A center bolster for six wheel trucks comprising a pair of longitudinally disposed members which are of I-beam shape in cross section the central portion of which members 60 are arched to accommodate the center axle of the truck, a pair of transversely disposed members integral with the ends of said longitudinally disposed members, which transverse members are channel shape in 65 cross section and arms projecting outwardly

from the connected ends of said pairs of members, which arms are box-shape in cross section.

5. A center bolster for six wheel truck frames cast in a single piece and comprising 70 a rectangular frame, the sides of which are arched to accommodate the center axle of the truck, an inverted U-shaped member connecting the arched portions of the sides of said frame, arms projecting laterally 75 from the corners of said frames, which arms are box-shape in cross section, and hollow members integral with the outer ends of said arms, which hollow members coöperate with the wheel pieces of the truck frame. 80

6. In a center bolster for six wheel trucks, a pair of longitudinally disposed members, the central portions of which are arched to accommodate the center axle of the truck, an inverted U-shaped member connecting the 85 arched portions of said longitudinally disposed members, a pair of transversely disposed members uniting the ends of said longitudinally disposed members, and laterally projecting arms at the ends of said longitudinally disposed members, which arms are 90 box-shape in cross section.

7. In a center bolster for six wheel trucks, a pair of longitudinally disposed members, the central portions of which are arched, a 95 pair of transversely disposed members uniting the ends of said longitudinally disposed members, laterally projecting arms at the ends of said longitudinally disposed members, which arms are box-shape in cross 100 section, and side bearing members on the arched portions of said longitudinally disposed members.

8. In a center bolster for six wheel trucks, a pair of longitudinally disposed members, 105 the central portions of which are arched, a pair of transversely disposed members uniting the ends of said longitudinally disposed members, laterally projecting arms at the ends of said longitudinally disposed members, which arms are box-shape in cross section, a transversely disposed member integral with and arranged between the central portions of said longitudinally disposed members and a center bearing on said last 115 mentioned transversely disposed member.

9. In a center bolster for six wheel trucks, a pair of longitudinally disposed members, the central portions of which are arched, a 120 pair of transversely disposed members uniting the ends of said longitudinally disposed members, laterally projecting arms at the ends of said longitudinally disposed members, which arms are box-shape in cross section, a transversely disposed member integral with and arranged between the central portions of said longitudinally disposed members, and side bearing members on the arched portions of said longitudinally disposed members. 125

10. A center bolster for six wheel car trucks, formed in a single piece and comprising a frame, a center bearing thereon, side bearings on the sides of the frame, and 5 arms projecting laterally from the ends of said frame, which arms are box-shape in cross section.

11. A center bolster for six wheel car trucks, formed in a single piece and comprising a frame a center bearing thereon, side bearings on said frame, arms projecting laterally from the ends of said frame, which 10 arms are box-shape in cross section, and hollow members on the ends of said arms, which 15 hollow members are adapted to coöperate with the side frames of the car truck.

12. A center bolster for six wheel trucks comprising a frame having side and end 20 pieces, the central portions of the side pieces being arched to accommodate the center axle of the truck, side bearings on said arched side pieces, a member connecting the arched portions of the side pieces, a center bearing 25 on said member arms projecting laterally from the corners of said frames, which arms are box-shape in cross section, and are adapted to coöperate with the wheel pieces of the truck frame, and the inner walls of 30 which box shaped arms are inset to provide brake head clearance spaces.

13. A center bolster for six wheel trucks comprising a frame having side and end

pieces, the central portions of the side pieces being arched to accommodate the center axle of the truck, side bearings on said arched side pieces, a member connecting the arched portions of the side pieces, a center bearing 35 on said member, arms projecting laterally from the corners of said frames, which arms are box-shape in cross section, and are 40 adapted to coöperate with the wheel pieces of the truck frame, and the inner walls of which box shaped arms are inset to provide brake head clearance spaces.

14. A center bolster for six wheel trucks 45 comprising a body formed of pairs of flanged side and end members, the central portions of said side members being arched to accommodate the center axle of the truck, side bearings formed on the arched portions 50 of said side members, arms integral with and projecting outwardly from the ends of said body, which arms are box-shape in 55 cross section, and said arms being provided on their inner sides with recesses which form brake head clearance spaces.

In testimony whereof I hereunto affix my signature in the presence of two witnesses, this 30th day of July, 1913.

CHARLES T. WESTLAKE.

DISCLAIMER.

1,102,620.—Charles T. Westlake, St. Louis, Mo. CENTER-BOLSTER FOR SIX-WHEEL CAR-TRUCKS. Patent dated July 7, 1914. Disclaimer filed September 5, 1914, by the assignee, *Double Body Bolster Company*.

Enters this disclaimer—

“To those claims in said specification which are numbered 1, 2, 3, 5, 6, 7, 8, 9, 10, 11, and 12, and which are in the following words, to wit:

“1. A center bolster for six wheel trucks comprising a rectangular frame the central portion of which is arched to accommodate the center axle of the truck, and arms projecting laterally from the corners of said frame, which arms are box-shape in cross section, and the outer ends of which are adapted to coöperate with the wheel pieces of the truck frame.

“2. A bolster for six wheel trucks comprising a body formed of pairs of flanged side and end members the central portions of which side members are arched to accommodate the center axle of the truck, and arms integral with and projecting outwardly from the ends of said body, which arms are box-shape in cross section.

“3. A center bolster for six wheel trucks comprising a pair of longitudinally disposed parallel flanged members the central portions of which members are arched to accommodate the center axle of the truck, a pair of transversely disposed parallel flanged members, and arms integral with and projecting outwardly from the end portions of said pairs of parallel members and which arms are box-shape in cross section.

“5. A center bolster for six wheel truck frames cast in a single piece and comprising a rectangular frame, the sides of which are arched to accommodate the center axle of the truck, an inverted U-shaped member connecting the arched portions of the sides of said frame, arms projecting laterally from the corners of said frame, which arms are box-shape in cross section, and hollow members integral with the outer ends of said arms, which hollow members coöperate with the wheel pieces of the truck frame.

“6. In a center bolster for six wheel trucks, a pair of longitudinally disposed members, the central portions of which are arched to accommodate the center axle of the truck, an inverted U-shaped member connecting the arched portions of said longitudinally disposed members, a pair of transversely disposed members uniting the ends of said longitudinally disposed members, and laterally projecting arms at the ends of said longitudinally disposed members, which arms are box-shape in cross section.

“7. In a center bolster for six wheel trucks, a pair of longitudinally disposed members, the central portions of which are arched, a pair of transversely disposed members uniting the ends of said longitudinally disposed members, laterally projecting arms at the ends of said longitudinally disposed members, which arms are box-shape in cross section, and side bearing members on the arched portions of said longitudinally disposed members.

“8. In a center bolster for six wheel trucks, a pair of longitudinally disposed members, the central portions of which are arched, a pair of transversely disposed members uniting the ends of said longitudinally disposed members, laterally projecting arms at the ends of said longitudinally disposed members, which arms are box-shape in cross section, a transversely disposed member integral with and arranged between the central portions of said longitudinally disposed members and a center bearing on said last mentioned transversely-disposed member.

“9. In a center bolster for six wheel trucks, a pair of longitudinally disposed members, the central portions of which are arched, a pair of transversely disposed members uniting the ends of said longitudinally disposed members, laterally projecting arms at the ends of said longitudinally disposed members, which arms are box-shape in cross section, a transversely disposed member integral with and arranged between the central portions of said longitudinally disposed members, and side bearing members on the arched portions of said longitudinally disposed members.

“10. A center bolster for six wheel car trucks, formed in a single piece and comprising a frame, a center bearing thereon, side bearings on the sides of the frame, and arms projecting laterally from the ends of said frame, which arms are box-shape in cross section.

“11. A center bolster for six wheel car trucks, formed in a single piece and comprising a frame, a center bearing thereon, side bearings on said frame, arms projecting laterally from the ends of said frame, which arms are box-shape in cross section, and hollow members on the ends of said arms, which hollow members are adapted to coöperate with the side frames of the car truck.

“12. A center bolster for six wheel trucks comprising a frame having side and end pieces, the central portions of the side pieces being arched to accommodate the center axle of the truck, side bearings on said arched side pieces, a member connecting the arched portions of the side pieces, a center bearing on said member arms projecting laterally from the corners of said frames, which arms are box-shape in cross section, and are adapted to coöperate with the wheel pieces of the truck frame, and said arms being provided with recesses which form brake head clearance spaces.”
